Primary Examiner—Clare E Heflin

(57) **CLAIM**

The ornamental design for a lighting fixture, as shown and described.

DESCRIPTION

FIG. 1 is a perspective view of a lighting fixture showing our new design;

FIG. 2 is a front view thereof, the rear view being a mirror image of the front view;

FIG. 3 is a left side view thereof;

FIG. 4 is a right side view thereof;

FIG. 5 is an enlarged top view thereof;

FIG. 6 is an enlarged bottom view thereof; and,

FIG. 7 is an enlarged cross-sectional view taken along line 7—7 in FIG. 3.

The broken line showings in the drawing are for illustrative purposes only and form no part of the claimed design.
